US00D931456S

(12) **United States Design Patent** (10) **Patent No.:** **US D931,456 S**
(45) **Date of Patent:** **** Sep. 21, 2021**

(54) **EAR CURETTE HOUSING**

(71) Applicant: **Ear Technology Corporation**, Johnson City, TN (US)

(72) Inventors: **Daniel R. Schumaier**, Elizabethton, TN (US); **Karlee D. Harrison**, Johnson City, TN (US); **George B. Waites, Jr.**, Fletcher, NC (US); **Samuel C. Scudder**, Asheville, NC (US)

(73) Assignee: **Ear Technology Corporation**, Johnson City, TN (US)

(**) Term: **15 Years**

(21) Appl. No.: **29/771,270**

(22) Filed: **Feb. 22, 2021**

(51) LOC (13) Cl. **24-02**

(52) U.S. Cl.

USPC **D24/147**

(57) **CLAIM**

The ornamental design for an ear curette housing, as shown and described.

DESCRIPTION

FIG. 1 is a perspective view of an ear curette housing showing our new design;

FIG. 2 is a right side elevation view thereof;

FIG. 3 is a left side elevation view thereof;

FIG. 4 is a top plan view thereof;

FIG. 5 is a bottom plan view thereof;

FIG. 6 is a rear elevation view thereof; and,

FIG. 7 is a front elevation view thereof.

The broken lines in FIGS. 1, 6 and 7 depict portions of the ear curette housing that form no part of the claimed design.

1 Claim, 2 Drawing Sheets
